FIG-2FIG-3FIG-4FIG-5FIG-6

The side of the dresser not shown is like the side shown, and the back is substantially plain and unornamented.

The dominant features of my design reside in those portions shown in full lines.

I claim:

The ornamental design for a dresser or the like, substantially as shown and described.
